ATTORNEY.

UNITED STATES PATENT OFFICE.

JAMES A. KLAHRE AND HENRY F. A. KLEINSCHMIDT, OF JOHNSTOWN, PENNSYLVANIA.

GAS-BURNER HOLDER.

1,372,145.

Specification of Letters Patent. Patented Mar. 22, 1921.

Application filed February 4, 1919. Serial No. 275,045.

To all whom it may concern:

Be it known that we, JAMES A. KLAHRE and HENRY F. A. KLEINSCHMIDT, residents of Johnstown, in the county of Cambria and State of Pennsylvania, have invented certain new and useful Improvements in Gas-Burner Holders, of which the following is a specification.

Our invention has relation to apparatus for use in handling gas burners such as the oxy-hydrogen and oxy-acetylene gas burners employed to cut metal and in locally heating metal articles.

One object of our invention is the provision of an articulate holder for gas burners having novel means whereby the burner is held and is manipulated to cause the flame emanating from the burner to travel in a single flat plane, and thereby sever the metal with a clean cut and narrow kerf.

Another object of the invention is to provide a holder for gas burners having improved means whereby the burner holder is detachably held in place while manipulating the burner and holder in the operation of the burner.

A further object of our invention is the provision of an articulate burner holder having the novel construction, arrangement and combination of parts shown in the drawings and to be more fully described hereinafter and particularly pointed out in the appended claims.

Referring now to the drawings forming part of this specification, Figure 1 is an elevation showing a burner holder embodying our invention and illustrating its application in holding a gas burner in position relative to a street car rail.

Fig. 2 is an elevation, at a right angle to that of Fig. 1 of the burner illustrated in Fig. 1.

In the accompanying drawings, the numeral 2 designates an oxy-hydrogen torch or burner, of any approved construction, as applied for use and held in place on a girder track rail 3 or other article, by means of a manually manipulated articulate burner holder embodying our invention. In the construction shown, the holder has a clamping shoe 4 provided with heels 5, 5 at the ends thereof, and each heel 5 has clamping faces 6, 6 and 7 on one side, and similarly formed clamping faces 8, 8 and 9 on the opposite side thereof, the faces

being formed in this way to facilitate the attachment of the holder to the work to be operated upon.

The shoe 4 has lugs or ears 10, 10 on one side, at or adjacent to the middle of the length thereof, to which the end of one branch of the forked clamping arm 11 is pivotally connected by means of a pin 12. The outer end of each of the two other branches of this arm, which are oppositely curved, has a hand screw 13 by which the shoe is detachably fastened to the rail 3.

By reference to Fig. 1 it will be seen that the faces 7 are in a plane at a right angle to that of the faces 6, 6 and that the faces 9 are arranged in a similar manner with respect to the faces 8, 8. When the shoe is clamped to the rail head, the faces 7 or 9, depending upon which are being used, automatically take a position at right angles to the gage line 14 of the rail.

Pivotally secured at one end to the end of one or the other of the heels 5 of the shoe, by means of a bolt 15, is a link or swinging arm 16 and the other end of the arm 16 is pivotally connected by a bolt 15 to one end of a second arm 17. The heels 5 are formed to permit attachment of the swinging arms to either end of the shoe. The other end of the arm 17 is pivotally connected by a bolt 15 to one end of a third arm 18. The articulated arms 16, 17, and 18 preferably are duplicates, so as to be interchangeable. The free end of the arm 18 is provided with clamping means whereby the torch or burner 2 is removably secured in operative position on the holder with the tip 2^a of the burner in position to be moved in a direction parallel to the cross sectional outline of the article operated upon. As shown the fastening includes a bolt 19 having a thumb nut 20 on its threaded end with a pair of washers 21, 21 between the nut 20 and end of the arm 18. The part of the bolt 19 extending through the arm 18 is larger in diameter than the part for the washers 21, and this enlarged portion is of such length that the bolt 19 will freely rotate in the hole in the arm 18 when the burner is tightly clamped in place between the washers 21. The abutting faces of the washers 21 preferably have transverse grooves or recesses 22 therein to receive the parts of the burner 2 clamped therebetween. The bolts 15 are like the bolt 19 in having the portion thereof adjacent to

- the bolt head of larger diameter than the balance of the bolt body to enable the arms to be pivotally fastened together and freely swing relatively about the axis of the bolt 5 as is necessary in using the holder, this being accomplished by rigidly fastening the bolt to the end of one arm and rotating the bolt in the hole in the adjacent end of the other arm.
- 10 In the operation of our improved apparatus one or the other of the clamping screws 13 will coact with the adjacent clamping faces on the heels 5 on one side or the other of the clamping shoe 4 to rigidly attach the burner holder in the desired position on the rail or other article to be operated upon by the torch or burner. The burner holder will then be in readiness for use.
- 15 In using the apparatus the operator will move the burner to maintain the flame issuing from the tip of the burner in cutting position with that part of the rail to which the burner is fastened. In moving the burner 20 to maintain the burner in cutting position the swinging arms 16, 17 and 18 of the burner holder compel the movement of the burner tip and flame in a single flat plane and in a plane at a right angle to the length 25 of the rail 3. In this way a straight cut is made in severing the rails, and the size of the kerf made by the flame is maintained 30 within the desired limits.
- 35 The relative length of the arms and the fact that they are all freely movable in parallel flat planes which are at right angles to the rail clamped by the burner holder enables the burner to be moved to the extent necessary to entirely sever a girder rail of 40 the type shown.
- 45 The advantages of our invention, which will be appreciated by those skilled in the art, arise from the arrangement of the burner holder in such manner as to guide the burner in a single flat plane and in this way 50 eliminate irregularities in severing articles which are unavoidable when the direction of movement as well as movement of the burner is manually controlled by the operator.
- 55 The apparatus is simple and effective, and is easily kept in repair.
- 60 Many modifications in the construction and arrangement of the parts forming this invention may be made. The form of the clamping shoe may be changed to suit 65 different varieties of work, and other changes may be made without departing from our invention as defined in the appended claims.
- 60 We claim:
1. A gas burner holder comprising at least three articulate holder arms adapted to be actuated manually, and clamping means pivotally mounted on opposite ends 70 of said articulated arms adapted to attach 65 the gas burner to work operated upon by the burner, said arms being pivotally connected for universal movement and to swing the burner in a single flat plane when the attached burner is manipulated.
2. A gas burner holder comprising articulate holder arms adapted to be actuated manually, means at one end of said articulated arms for attaching the gas burner to said arms, a work engaging shoe at the other end of said arms, and a clamping arm pivotally mounted on said shoe, said shoe and said arm coacting to attach said holder to the work operated upon by the burner, said articulate arms being pivotally connected 75 to swing the burner in a single flat plane when the gas burner is manipulated.
3. A gas burner holder comprising at least three holder arms pivotally secured together and arranged to be actuated manually, means at one end of said pivoted arms for attaching the gas burner to said arms, a work engaging shoe at the other end of the arms, and a clamping arm pivotally mounted on said shoe, said shoe and said clamping arm coacting with said arms to attach the holder to work operated upon by the burner, said holder arms being adapted to swing the burner in a single flat plane when manipulating the gas burner, and said shoe having 80 means for alining the holder on the work.
4. An articulate gas burner holder comprising a plurality of pivotally connected arms, a clamp pivotally mounted on one end of the connected arms for detachably connecting the burner thereto, a clamping shoe pivotally mounted on the other end of said connected arms, and clamping arms pivotally mounted on said shoe for fastening the holder to the work, said holder being adapted to move said burner in a single flat plane 85 relative to the work when the burner is being manipulated.
5. A manually operated gas burner holder comprising a plurality of pivotally connected arms, a clamp pivotally mounted on one end of the connected arms for detachably connecting the burner thereto, a clamping shoe pivotally mounted on the other end of said connected arms, and clamping arms pivotally mounted on said shoe for fastening the holder on the work, said holder being constructed and arranged to move said burner in a single flat plane when the burner 90 is being manipulated, and means on said shoe for automatically alining the holder and burner on the work when clamping the shoe to the work.
- In witness whereof, we have hereunto 95 signed our names.
- JAMES A. KLAHRE.
HENRY F. A. KLEINSCHIMIDT.
